UNITED STATES PATENT OFFICE.

HERMAN L. SCHNEIDER, OF CHICAGO, ILLINOIS.

CARPET AND RUG BEATING APPARATUS.

Application filed June 3, 1926. Serial No. 113,451.

My present invention has to do with the beating of carpets, rugs and the like for the removal of dust and dirt therefrom; and it contemplates the provision of a highly efficient apparatus for beating rugs, carpets and the like.

Other objects and practical advantages of the invention will be fully understood from the following description and claims when 10 the same are read in connection with the drawings, accompanying and forming part of this specification, in which:—

Figure 1 is a view, partly in elevation and partly in longitudinal vertical section, of the 15 apparatus constituting the best practical embodiment of my invention that I have as yet devised.

Figure 2 is an elevation showing one end of the apparatus.

Figure 3 is an elevation showing the opposite end of the apparatus.

Similar numerals of reference designate corresponding parts in all of the views of the drawings.

Among other elements my novel apparatus comprises a main frame 1 which may be of the structure illustrated or of any other construction compatible with the purpose of my invention. The said main frame 1 is 30 equipped with a side wall 2 and a top wall 3 and is also equipped with a side wall 4 made up in part of drop doors 5 and 6, the drop door 5 being to enable an operative to enter between the walls 1 and 4 for purposes of repair or for lubricating parts of the apparatus, and the door 6 being for the introduction and removal of carpets, rugs or other articles to be beaten.

It will be appreciated from the foregoing 40 that the apparatus is open at its opposite ends and I would here have it understood that my improvement comprises a blower fan 7 at one end of the apparatus. The said blower fan 7 is preferably arranged in guard casing 8 and is adapted to send a blast of air longitudinally through the central portion of the apparatus in the direction indicated by the large arrow in Figure 1. Said blower fan 7 is fixed to a shaft 9 having pulleys 10 and 11 at its ends, the pulley 11 being

for connection to any appropriate motor, not illustrated. The pulley 10 is adapted to receive belts 12, Figure 2, and the said belts 12 are designed to transmit motion to pulleys 13 on longitudinal shafts 14, the said 55 shafts 14 being equipped at intermediate points in their lengths with tappets 15, as appears in Figures 1 and 3.

Fulcrumed at 16 on the main frame or rather on longitudinal rods 17 carried by 60 the main frame are swingable beaters 18 each of which is provided with a blade or comparatively wide portion 19, Figure 1. Retractile springs 20 are interposed between and connected to the upper arms of the 65 beaters 18 and portions of the main frame, the said retractile springs 20 having for their function to suddenly pull the upper arms of the beaters inwardly when the lower arms of the beaters are released by their 70 complementary tappets 15.

In order that some of the beaters 18 may be rendered idle when desirable, as when a carpet or rug is not sufficiently wide to enable all of the beaters to engage the same, 75 I provide hold back springs 21, one to each beater 18. The said springs 21 are connected to and extend outwardly from the upper arms of the beaters 18, and the outer ends of the springs 21 are connected to threaded 80 rods 22 guided in the main frame 1 and equipped outwardly beyond the casing walls 2 and 4 with lever nuts 23. Manifestly when the operative of the apparatus desires to place any one or more of the beaters 18 out 85 of commission, it is simply necessary for the operative to manipulate appropriate nuts 23 so as to draw certain springs 21 and the upper arms of the beaters 18 connected to said springs outwardly, so that the beaters 90 referred to will not be caused to act against a rug, carpet or the like positioned in the apparatus.

Mounted in the upper portion of the main frame and casing is a roller 30 through the 95 medium of which a rug, carpet or the like may be moved in the apparatus between the sets of beater blades 19 for the presentation of different parts of the rug, carpet or the like to the said blades. The said roller is 100

provided with rubber faced peripheral portions 31 and is also provided intermediate of said peripheral portions 31 with hooks 32 or other appropriate devices for taking hold 5 of a rug, carpet or the like with a view to assuring movement of the rug, carpet or the like with the roller 30. Mounted in vertically adjustable bearings 40 and located above the roller 30 is an idler roller 41 which 10 is preferably, though not necessarily, provided with a peripheral portion 42 of rubber, and is adapted, by virtue of the vertical adjustability of its bearings 40 to accommodate itself to rugs, carpets and the like 15 of different thicknesses.

Arranged within the frame and casing and at opposite sides of the roller 30 are shoes 50, spaced from the perimeter of the roller 30 and designed to guide a rug, carpet or 20 the like after the manner indicated by the dotted lines 51 in Figure 2.

The main shaft 9 is connected by a belt 60 on appropriate pulleys with a short shaft 61 upon the outer end of which is a miter 25 gear 62, Figures 1 and 3. The gear 62 is disposed vertically and is meshed with a horizontal miter gear 63 and a short shaft journalized in a bracket 64, and the said short shaft is equipped at its upper end with a 30 miter gear 65. The shaft of the roller 30 is designated by 30^a, and is equipped with loose miter gears 30^a and 30^b, located at opposite sides of the miter gear 65. The said miter gears 30^a and 30^b are fixed to a sleeve 35 30^c, and the said sleeve 30^c is splined on the shaft 30 or is otherwise associated with the shaft 30 so as to turn therewith and be capable of moving endwise thereof. Manifestly when the gear 30^a is meshed with the 40 gear 65, the roller 30 will be rotated in one direction, while when the gear 30^b is meshed with the gear 65 the roller 30 will be turned in the opposite direction. The sleeve 30^c is designed to be shifted endwise through the 45 medium of a hand lever 70, fulcrumed at 71, and hence it will be understood that incident to the operation of the apparatus, an operative is enabled to move a rug, carpet or the like in opposite directions so as to present 50 different portions of the rug or carpet to the blades 9 of the beaters 18.

It will be apparent from the foregoing that without being unduly expensive in construction, my novel apparatus is highly efficient in operation, and is adapted to be operated with but little attention.

I have entered into a detailed description of the construction and relative arrangement of the parts embraced in the present 60 and preferred embodiment of my invention in order to impart a full, clear and exact understanding of the said embodiment. I do not desire, however, to be understood as limiting myself to the construction disclosed, my invention being defined by my 65

appended claims within the scope of which modifications may be made without departure from my invention.

Having described my invention, what I claim and desire to secure by Letters Pat- 70 ent, is:

1. In an apparatus for beating rugs, carpets and the like, and in combination, a frame, a casing carried by the frame and having sides spaced apart and also having a top, side doors, a roller mounted in the frame and adapted to move a carpet, rug or the like, fed thereover, a gravitational roller mounted above the first-named roller and adapted to press a carpet, rug or the like against the latter, guide shoes at opposite sides of and spaced from the first-named roller, means for rotating the first-named roller in opposite directions, said means controllable by an operative, sets of oscillatory beaters having beater arms and tappet arms, spring means associated with the beater arms and the frame for forcibly moving said beater arms against a carpet, rug or the like, rotary tappet means arranged to cooperate with the tappet arms of the beaters to move the beater arms thereof away from a rug, carpet or the like, means associated with the beater arms of the beaters and the frame, whereby any one of the beater arms may be rendered idle, and a blower fan located at one end of the frame and adapted to force air longitudinally through the frame and alongside the beaters. 100

2. In an apparatus for beating rugs, carpets and the like, and in combination, a frame, a rug or carpet supporting and moving roller mounted in the frame, guide means at opposite sides of and spaced from said roller, a gravitational roller superposed upon the first-named roller, longitudinal shafts mounted in the frame and spaced apart, oscillatory beaters mounted at intermediate points in their lengths on said longitudinal shafts and having blades on their beater arms and also having lower tappet arms, retractile springs interposed between and connected to the beater arms and the frame, threaded rods mounted in the frame, nuts on said rods outwardly beyond the frame, springs interposed between said rods and the beater arms, longitudinal shafts carried by the frame and located below the first-named longitudinal shafts, tappets on the second-named longitudinal shafts and arranged to cooperate with the tappet arms of the beaters, means for rotating the second-named shafts, and operative controlled means for turning the first-named roller in opposite directions. 110

3. In an apparatus for beating carpets, rugs and the like, the combination with a frame, roller means in the frame and adapted to support a carpet, rug, or the like in 120 125 130

position to be beaten, a set of beaters mounted in the frame and having beater arms and also having tappet arms, rotary tappets for cooperating with the tappet arms of the beaters, and spring means connected with the beater arms of the beaters for the forcible movement of the same against a carpet,

rug, or the like, of threaded rods mounted in the frame, nuts mounted on said rods outwardly beyond the frame, and retractile springs interposed between and connected to the beaters and said threaded rods. **10**

In testimony whereof I affix my signature.

HERMAN L. SCHNEIDER.
